UNITED STATES PATENT OFFICE.

WILHELM HEIDELMANN, OF STUTTGART, GERMANY.

DEVICE FOR FEEDING ENVELOPES.

SPECIFICATION forming part of Letters Patent No. 443,093, dated December 23, 1890.

Application filed May 27, 1890. Serial No. 353,315. (No model.)

To all whom it may concern:

Be it known that I, WILHELM HEIDELMANN, a subject of the Emperor of Germany, residing at Stuttgart, Germany, have invented a new and useful Improvement in Devices for Feeding Envelopes, of which the following is a specification.

This invention relates to an apparatus for automatically lifting separate envelopes from a pile sufficiently for feeding the same to the grippers of a printing-press.

The object of my invention is to provide a device in which the envelopes are grasped at one of their longitudinal edges, near the side edges and under the open or sealed flap, and thus fed to the press for printing. By this arrangement the objection heretofore existing in envelope-feeding devices for printing-presses, whereby when the open flap was caught under the sealed flap the said devices would fail to operate and a stoppage of the machine was necessitated, is entirely obviated.

In the apparatus heretofore employed for automatically feeding envelopes to printing-presses which are based on the idea of grasping the projecting sealing-flap of the envelope by a suitable arrangement and to draw it forth from the pile and feed it to the press it is a frequent occurrence that the flap adheres to the body of the envelope, or the point of the open flap becomes caught under that of the sealed flap, in both of which cases the sealing-flap is prevented from depending from the body, and it becomes impossible to grasp the same. Such envelopes must first be separated from the pile by hand before the apparatus can continue in its operation, a considerable loss of time being the result. My apparatus entirely obviates this objection.

In the drawings accompanying this specification, Figures 1 and 2 represent, respectively, a sectional side elevation and a front elevation of an apparatus embodying my invention, the parts being shown as occupying the position after an envelope has been lifted from the pile; Figs. 3 and 4, similar views, the parts being shown in the position they occupy before an envelope is withdrawn. Figs. 5 and 6 illustrate details of the apparatus.

The feeding of the envelope to be printed

to the press is performed in two steps and in such a manner that the same is by suitable devices first pushed or shoved out of the pile sufficiently to be then grasped by the grippers *i i* of the press, to be farther carried along. 55 My invention resides in this lifting out of each separate envelope from the pile, and will now be described in detail.

The envelopes, as shown, preferably rest upon an inclined table *b*, having an upwardly-extending wall *a*, against which the lower edges of the envelopes rest; but any suitable holder for the envelopes will answer. The ejecting-slide *c* is arranged so as to reciprocate below the table *b* and grasp the lower-most envelope, thus feeding them out of the holder or table, this ejecting-slide *c* having two prongs *c'* extending along both sides of table *b* and embracing the same and provided on both sides with the thin ejecting-jaws *d*, 60 which extend inwardly from the prongs *c'* and above the table *b*, (see Figs. 1 and 3,) which are adjustable to correspond to the breadth of the envelopes held in their positions of adjustment by set-screws *d'*. These jaws have 65 the form indicated in Fig. 6—that is to say, they are beveled at their inner or forward sides, bent over to some extent, and sharpened to form a knife-edge. These knife-edges enter between the open flap or the sealed flap 70 (the latter not adhering to the body for about ten to fifteen millimeters from the side edges) and the body, according as it is desired to print along the one or the other longitudinal edge of the envelope, when in the forward 75 movement of the ejecting-slide *c*, by means of the crank *f*, the jaws *d* glide close to the back of the envelope. An envelope is thus advanced accurately and sufficiently to be grasped by the grippers *i i* of the press, and 80 thus carried to the printing-point.

In order to prevent the accidental advance of a number of envelopes at once two fixed holders *g* are attached at the forward side of the apparatus, said holders being adjustable 85 to correspond to the thickness of the envelopes, so that only one envelope can pass the same, the others being held back by the holders.

To diminish friction of the envelope to be 90

advanced upon the feed-table *b*, a ledge or strip *h*, over which the envelope glides, is provided at its front side.

What I claim, and desire to secure by Letters Patent, is—

1. In an envelope-feeding device, the combination, with an envelope-holder containing a pile of envelopes, of an ejecting-slide below the envelope-holder and having prongs and ejecting-jaws extending inwardly therefrom, substantially as shown and described.

2. In an envelope-feeding device, the combination, with an envelope-holder, of an ejecting-slide having prongs and adjustable ejecting-jaws extending inwardly therefrom, substantially as shown and described.

3. In an envelope-feeding device, the combination, with an envelope-holder, of a reciprocating ejecting-slide *c*, provided with ejecting-jaws *d*, having beveled inner corners bent 20 upwardly and sharpened to form knife-edges, substantially as set forth.

In testimony whereof I have signed this specification in the presence of two subscribing witnesses.

WILL. HEIDELMANN.
